UNITED STATES PATENT OFFICE

BRUNO ANTONIO QUINTAVALLE, OF MILAN, ITALY, ASSIGNOR TO FABBRICA ITALIANA MAGNETI MARELLI SOCIETA ANONIMA, OF MILAN, ITALY, A COMPANY OF ITALY

IGNITION MAGNETO

Application filed May 12, 1930, Serial No. 451,732, and in Italy June 25, 1929.

It is known that in ignition systems of internal combustion engines the ignition point must be advanced with respect to engine piston dead centre and more the number of 5 R. P. M. of the engine is high, more said advance must be large.

The present invention has for its object a device for securing the ignition advance by 10 altering the angle between the magneto rotor and the engine crank shaft, the primary circuit being thus broken always in register with the same position of the magneto rotor with respect to its inductor field, and therefore the spark having always its maximum intensity 15 whatever is the advance imparted to ignition.

On the annexed drawings is illustrated by way of example an embodiment of the present invention, and

Figure 1 is a fragmentary central longitudinal section of a magneto embodied in 20 accordance with the present invention;

Figure 2 illustrates a separate part on an enlarged scale and in detail;

Figure 3 illustrates another separate part 25 on an enlarged scale and in detail;

Figure 4 is an end view of Figure 3;

Figure 5 is a detail of the ignition controlling device with parts in section.

In the construction illustrated the magneto 30 comprises a rotor 1 mounted on a sleeve 2 which is pivoted in the magneto frame 28 by means of bearings 3, 4; said sleeve 2 has at one end splines providing inward teeth 5 with their faces flat and parallel with axis of rotation.

Inside sleeve 2 a hollow shaft 6 is mounted loose therein, said shaft 6 providing a cone 7 for fastening thereon a magneto-rotor-actuating pinion or coupling (not shown); said shaft 6 has large-pitch helical grooves 9 in its internal open end while at the closed end of its hollow it has a centering stud 10.

In screw grooves 9 of hollow shaft 6 is engaged a cooperating screwthread 11 of a bushing 12 which seats in the hollow of shaft 6 and has at its end straight teeth 13 engaging those 5 of sleeve 2, to connect bushing 12 with sleeve 2 in rotation while providing for their respective longitudinal motion.

50 A spring 8 positioned on stud 10 of shaft

6 holds bushing 12 forced towards a shoulder 2' provided by sleeve 2.

A circuit breaking device, of conventional construction and not shown, is located in chamber 27 of magneto frame and it is operated by a cam 26 solid with sleeve 2; it includes a hammer (not shown) which under timed action of cam 26 causes a movable contact to separate from a cooperating stationary contact, the primary circuit being thus interrupted.

In casing 14 removably mounted on the magneto end, straight slots 15 parallel with the axis of sleeve 2 are provided, and in said slots 15 the ends of a cross member 16 are engaged said cross member acting on a central stem 17 whose opposite end abuts against the end of bushing 12. Within casing 14 a box 18 is mounted to rotate, the wall of the same having helical slots 19 which also are 70 engaged by cross member 16 and said box 18 may be deviated from outside by means of arm 25 loose on nose 20 of casing 14 and engaged on pins 21 projecting from box 18 through slots 22 of casing 14 which slots are 75 shaped as a circle concentric with stem 17; arm 25 is made solid with sleeve 18 by means of split washer 23 engaging notches of pins 21 and bearing on the face of hub 25' of arm 25; hub 25' has a series of holes 24 intended to receive pins 21 for the purpose of adjusting the normal position of arm 25 in accordance with requirements to be complied with in different types of engines.

When magneto shaft 6 is driven in rotation 80 in the direction the magneto is intended to (left-hand in the illustrated construction as seen from cone 7), shaft 6 drives bushing 12 in rotation; bushing 12 in turn drives sleeve 2 and rotor 1 into rotation by means of its teeth 90 13 in engagement with those 5 of sleeve 2.

Assuming stem 17 to be entirely retracted within its seat and therefore to be inoperative, and shaft 6 be connected under the required angle with engine crank shaft, the 95 magneto is operating with maximum advance because in exemplified case the normal arrangement of parts secures maximum advance, that is normal running conditions of the engine.

When advance angle is to be altered, arm 25 is actuated, whose actuating means (not shown) include a device of any known construction holding said arm in any particular position imparted thereto; then deviation of arm 25 is imparted by pins 21 to box 18 whose helical slots 19 move with respect to longitudinal grooves 15 of stationary casing 14; the transverse member 16, being engaged at the same time in slots 19 and grooves 15, is caused to move parallel to itself and therefore it moves stem 17 against bushing 12 to shift this latter along its axis against action of spring 8 while its teeth 13 slide along those 5 of sleeve 2.

The longitudinal displacement of bushing 12 with respect to hollow shaft 6 which can not revolute faster nor slower it being under preponderating engine action, causes screw-thread 11 of bushing 12 to screw into that 9 of shaft 6 and said bushing 12 to move angularly with respect to said shaft 6; owing to engagement of bushing 12 and sleeve 2 carrying rotor 1 by said teeth 13 and 5 said rotor 1 is shifted angularly with respect to engine crank shaft.

Thus the desired value is imparted to advance while the respective position of rotor 1 with respect to field of inductor 29 and the breaking point of primary circuit are unaffected, because the breaking cam 26 is solid in an unchanged position with respect to magneto rotor 1.

On arm 25 being further shifted in the same direction the advance angle is still reduced, while when arm 25 is moved in opposite direction spring 8 holds bushing 12 forced against stem 17 to finally carry it again against shoulder 2' of sleeve 2 to restore initial conditions of angular connection intermediate rotor 1 and shaft 6 and maximum angle of advance.

Of course the described arrangement is given merely by way of example and is able to be altered within the spirit of appended claims, say in respect of engagement intermediate driving shaft and rotor and advance control device.

What I claim as my invention and desire to secure by United States Letters Patent is:

1. An ignition magneto for combustion engines comprising a stator, a rotor rotatable in said stator and having a splined bore, a hollow shaft having a screwthreaded bore, a spindle having a splined portion engaging said rotor splined bore and a screwthreaded portion engaging said shaft screwthreaded bore, and means for shifting longitudinally said spindle.

2. An ignition magneto for combustion engines comprising a stator, a rotor rotatable in said stator and having a bore comprising a plain portion and a splined portion, a hollow shaft loose in said rotor plain bore and having a screwthreaded bore, an endwise movable spindle having a screwthreaded por-

tion engaging said shaft screwthreaded bore and a splined portion engaging said rotor splined bore, and means for shifting longitudinally said spindle.

3. An ignition magneto for combustion engines comprising a stator, a rotor rotatable in said stator and having a bore comprising a plain portion and a splined portion, a hollow shaft loose in said rotor plain bore and having a screwthreaded bore, an endwise movable and hollow spindle having a screwthreaded portion engaging said shaft screwthreaded bore and a splined portion engaging said rotor splined bore, a spring in said hollow shaft and spindle moving them away from each other, a stem endwise movable in said rotor and abutting on said spindle and means for shifting said stem and spindle against said spring.

4. An ignition magneto for combustion engines comprising a stator, a rotor rotatable in said stator, a shaft for driving said rotor, a spindle having a helicoidal groove engaged with either said rotor or shaft and splines engaged with the other of said shaft or rotor, a stem engaging said spindle for shifting it longitudinally, a stationary member solid with said stator and a second member rotatable with respect to said stationary member, one of said members having sloping engaging means and the other one having engaging means parallel with the axis of said rotatable member, a part engaged with both said first and second named engaging means and acting on said stem, and means for actuating said rotatable member.

5. An ignition magneto for combustion engines comprising a stator, a rotor rotatable in said stator, a shaft for driving said rotor, a spindle having a helicoidal groove engaged with either said rotor or shaft and splines engaged with the other of said shaft or rotor, a stem engaging said spindle for shifting it longitudinally, a stationary member solid with said stator and a second member rotatable with respect to said stationary member, one of said members having sloping engaging means and the other one having engaging means parallel with the axis of said rotatable member, a part engaged with both said first and second named engaging means and acting on said stem, pins projecting from said rotatable member and an actuating arm engaged with said pins.

6. An ignition magneto for combustion engines comprising a stator, a rotor rotatable in said stator, a shaft for driving said rotor, a spindle having a helicoidal groove engaged with either said rotor or shaft and splines engaged with the other of said shaft or rotor, a stem engaging said spindle for shifting it longitudinally, a stationary member solid with said stator and a second member rotatable with respect to said stationary member, one of said members having sloping

engaging means and the other one having engaging means parallel with the axis of said rotatable member, a part engaged with both said first and second named engaging means 5 and acting on said stem, pins projecting from said rotatable member and each having a notch, an actuating arm having holes for engagement by said pins and a member engaging said notched pins for clamping said arm 10 thereon.

7. An ignition magneto for combustion engines comprising a stator, a rotor rotatable in said stator and having a bore comprising a plain portion and a splined portion, a hollow shaft loose in said rotor plain bore and having a screw-threaded bore, an endwise movable and hollow spindle having a screw-threaded portion engaging said shaft screw-threaded bore and a splined portion engaging 20 said rotor splined bore, a spring in said hollow shaft and spindle moving them away from each other, a stem endwise movable in said rotor and abutting on said spindle, a stationary member solid with said stator and 25 a second member rotatable with respect to said stationary member, one of said members having sloping engaging means and the other one having engaging means parallel with the axis of said rotatable member, a part engaged 30 with both said first and second named engaging means and acting on said stem, pins projecting from said rotatable member and each having a notch, an actuating arm having holes for engagement by said pins and a member engaging said notched pins for clamping 35 said arm thereon.

8. An ignition magneto for combustion engines comprising a stator, a rotor rotatable in said stator and having a bore, a hollow shaft 40 extending in a portion of said rotor bore, a spindle extending partly in said rotor bore and partly in said hollow shaft, co-operating teeth in said rotor bore and spindle and in said hollow shaft and spindle said teeth providing a spiral engagement between said 45 rotor and shaft, and means for shifting longitudinally said spindle.

9. An ignition magneto for combustion engines comprising a stator, a rotor rotatable in said stator and having a bore, a hollow shaft extending in a portion of said rotor bore, a hollow spindle extending partly in said rotor bore and partly in said hollow shaft, co-operating teeth in said rotor bore and spindle 55 and in said hollow shaft and spindle said teeth providing a spiral engagement between said rotor and shaft, a spring in said hollow shaft and spindle tending to move them away from each other, a stem movable endwise in said rotor and abutting on said spindle, and means for shifting longitudinally said stem and spindle against the action of said spring. 60

10. An ignition magneto for combustion engines comprising a stator, a rotor rotatable in said stator and having a bore comprising a

plain portion, inward teeth on another portion of said rotor bore, a hollow shaft loose in said plain portion of said rotor bore, inward teeth extending from the surface of said shaft bore, an endwise movable spindle having teeth engaging said inward hollow shaft teeth and teeth engaging said inward rotor bore teeth, said teeth of said spindle and said inward teeth of said rotor bore and hollow shaft providing a helicoidal engagement 70 between said shaft and rotor, and means for shifting longitudinally said spindle.

In testimony whereof I have signed my name to this specification.
